GLASS CUTTING MACHINE AND THE LIKE

Thomas McDowell, Utica, Ohio

Application June 27, 1932, Serial No. 619,580

10 Claims. (Cl. 33—32)

My invention relates to machines for cutting glass and the like sheet material, particularly to a power operated machine of this type, and an important object of my invention is to provide a machine of this type which is not only rugged and efficient, but which accurately cuts large sheets of glass and the like into smaller strips or forms.

Other objects and advantages of my invention will be apparent from a reading of the following description in connection with the drawings, wherein for purposes of illustration I have shown a preferred embodiment of the invention.

In the drawings:—

15 Figure 1 is a general side elevational view of the embodiment.

Figure 2 is a top plan view of Figure 1.

Figure 3 is a longitudinal vertical sectional view taken just inwardly of the large toothed wheel 20 shown in Figure 1.

Figure 4 is a transverse vertical sectional view through the brush holder mechanism.

Figure 5 is a transverse vertical sectional view similar to Figure 4.

25 Figure 6 is a diagrammatic representation of the wiring of the device.

Figure 7 is a longitudinal vertical sectional view approximately on the line 7—7 of Figure 5.

Figure 8 is an enlarged top plan view of the motor support and adjacent parts with the motor removed.

Figure 9 is an enlarged elevational view of the side of the embodiment opposite that shown in Figure 1.

35 Figure 10 is a longitudinal vertical sectional view through the outside portion of the structure shown in Figure 9.

The embodiment comprises generally a stationary bed plate of such material that it will not scratch the glass or the like to be cut and upon which it is to rest. This bed plate is provided at one end with a convenient handle on which is mounted an electric switch. On the bed plate is also mounted a block which is provided in two 45 sides with grooves or channels in which move bearings which carry a motor driven slide which carries a cutting wheel or diamond point for cutting the glass or the like as the slide travels backwardly and forwardly under the control of the operator, whereby large sheets of glass or the like may be accurately and quickly marked off or cut, and other accurate operations performed which it is not ordinarily possible to perform by the manual means now in use.

55 Referring in detail to the drawings, wherein

like numerals refer to like parts throughout the same, the numeral 5 generally designates the elongated, narrow bed plate which is provided with the reduced portion 6 at one end in the form of a handle to be gripped by the operator 5 in placing and holding the machine in place. Upon this handle is mounted a push button or other suitable type of switch 7 the manner of operation of which will be subsequently described. At the point where the handle 6 merges into the 10 main body of the bed plate 5 there is provided a double-pole double-throw switch 8, the function of which will also be subsequently described, in connection with the operation of the machine under the control of the operator thereof. 15

Longitudinally and approximately centrally on the base or bed plate there is disposed an elongated squared preferably metallic block 9 of a length slightly longer than the length of the cuts which may be desired to make. The block 9 is 20 provided in its upper face with a channel 10 and its right hand face with a channel 11 extending the length thereof. In each of the channels there is arranged a roller 12, 13, respectively. Upon and against the block 9 there slides a slide of L- 25 shaped cross-section which is generally designated 14. This slide 14 is comparatively short and slides on the upper face and right hand face of the block 9 and upon the upper surface of the base as can be clearly seen in Figure 5. The 30 rollers 12, 13 extend into notches formed in the slide and corresponding in position to the channels in the block 9. The outer side of the slide 14 has arranged thereon an adjustable block 15 which carries the cutter generally designated 16 35 which will be subsequently described in detail.

At the right hand marginal portion of the upper face of the slide 14 there is mounted an electric motor 17 which has its drive shaft 18 extending toward the opposite side of the machine and provided with a pinion 19 meshed with a large gear 20 carried on a shaft 21 journaled in a standard 22 which is carried by frame means 23 fixed to the left hand side of the slide 14 so as to move with the slide relative to the block 9 and base 5. The shaft 21 carries, inwardly of the standard 22, a small fixed pinion 24 which is meshed with another pinion 25 carried by a stud shaft 26 which is mounted within the frame means 23 and on the slide 14. 45

The pinion 25 is meshed with a rack 27 which is formed on the upper edge of a rack bar 28 attached by suitable means to the left hand side of the block 9. By this arrangement, actuation of the motor 17 will cause rotation of the train 55

of gears mentioned on the rack 27, whereby the slide 14, carrying the motor and the cutter will be caused to travel in either direction relative to the length of the block 9 and the base plate 5.

b. The double-pole double-throw switch 8 has its points connected to four contact rails 29, 30, 31 and 32 which are arranged in this order spaced downwardly and projecting laterally from the side of a dielectric block 33 which is mounted by 10 suitable means 34 to the outside of the rack bar 28 and as can be clearly seen in Figure 4, the rack bar 28 being connected by suitable means 35 which pass through it into the block 9.

The motor 17 is wired to four brushes 36, 37, 15 38 and 39 carried by the bracket 40 depending from the frame 23, which wipe the contact rails 29, 30, 31 and 32, the rails being connected to a source of electrical energy through the double-pole, double-throw switch 8 as shown in Figure 6. Suitable cables, four in number, generally designated 42 lead from the brushes to the motor. The to and fro motion of the slide relative to the block and base plate may be controlled as desired by the operator by throwing the arm 20 of the switch 8 to one side or the other.

The cutter generally designated 16 is mounted on the adjustable block 15 already mentioned, which is laterally adjustable relative to the slide 14. The cutter comprises the frame 43 attached 30 to the outer end of the block 15 by a dovetail tongue 53 which slides vertically in a dovetail slot in the outer end of the block 15, as indicated in Figure 8. A vertical set screw 54 carried by a portion of the frame 43 which overhangs the block 15 is arranged to engage the top of the block 15 for adjusting the frame 43 vertically relative to the block 15. Seen from above the frame 43 is U-shaped. Seen from the outer end, the frame 43 is L-shaped. A crescent shaped carrier 45 is pivoted as indicated at 44 between the legs and under the bight portion of the frame 43, upon which is mounted the cutter proper 46 which slides vertically through the middle of the carrier and has a diamond point or a disk 47 at its 40 lower end for engagement with the work. A plate 48 is normally downwardly maintained by springs 49 on bosses on the carrier, slides on the reduced portion 50 of the cutter 46 and abuts a shoulder thereon, and normally rests upon the upper side of the crescent carrier. A member 51 straddling the legs of the frame 43 carries a vertical adjustment screw 52 for engaging the free end of the crescent carrier 45 for adjusting it toward the work. Compensatory vertical movement of the cutter 46 is provided for by its 50 slide mounting on the carrier and the springs 49. For lateral adjustment of the block 15 and consequently of the cutter 46 relative to the block 9, there is provided at either side of the block 15 a horizontal laterally extending rod 55, 56, respectively, on which slide lugs 57, 58, respectively, projecting from the opposite sides of the block 15 and provided with set screws engaging the rods for maintaining the lateral adjustment 60 of the block 15. These set screws are indicated in Figure 5 by the numeral 59.

It will be obvious that the cutter overhangs the side of the base 5 and that with the means provided the cutter or diamond point may be adjusted to proper distance from the side of the base or bed plate 5 for cutting strips of glass or the like in the manner and in the size desired. As the cutter is carried to and fro in contact with the material to be cut, the nature of the structure 70 and its operations will cause the cuts made to

be accurate throughout their length, as will be obvious.

Reference to Figure 6 will disclose the manner of wiring the device of the invention so that the motor may be easily reversed and controlled for starting, stopping, and controlling the to and fro motion of the slide carrying the cutter. As in Figure 4, the numerals 29, 30, 31 and 32 in Figure 6 designate the contact rails, the numeral 17 designates the motor, and the numeral 8 generally designates the double-pole, double-throw reversing switch mentioned. It will be obvious that the conductors generally designated 42 are connected to opposite sides of the field of the motor 17 and to alternate contact rails. To these 15 contact rails the points of the switch 8 are connected in alternate manner as shown. In the position of the switch 8 indicated in Figure 6 the rails 32 and 29 are energized, while the rails 30 and 31 are deenergized, whereby the motor will be 20 caused to rotate in one direction. In an opposite position of the switch 8 the remaining contacts of the switch 8 are bridged and the remaining contact rails are energized to the exclusion of the others, whereby the motor is reversed or put into 25 rotation in the opposite direction. Since the energization of the contact rails in pairs is in the control of the operator of the machine, it will be obvious that a cut in the work may be made 30 in either direction of movement of the slide at 30 will. The push button switch 7 is so arranged in the circuit that when the switch 8 is set in one position, the push button 7 may be utilized for controlling the source of electrical energy there- 35 to, so as to energize or deenergize the contact rails and the switch 8 at the will of the operator.

If desired, the switch 8 and the switch 7 may be combined in a single organization, wherein the switch 8 will be arranged to have a neutral position corresponding to the off position of the switch 7, as well as the reversing function.

Though I have shown and described herein a preferred embodiment of the invention, it is to be definitely understood that I do not desire to limit the application of the invention thereto, and any change or changes may be made in material and structure and arrangement of parts, within the spirit of the invention and the scope of the subjoined claims.

What is claimed is:—

1. A cutter for sheet glass, said cutter comprising a base for resting on the sheet glass, a longitudinal block on the top of said base and spaced from a side of said base, a slide having a part sliding on the top of said block, a second part sliding against the side of said block against the mentioned side of the base, and a third part extending from said second part and sliding on the top of the base, the slidably engaged surfaces of the first mentioned part and said second part and the slidably engaged surfaces of the top and of said mentioned side of the block being formed with registering longitudinal grooves, rollers in said registering grooves, said rollers being of sufficient diameter to extend in and between each pair of registering grooves and thereby positively prevent separation of said slide from said block and said base by relative transverse movement, and glass cutting means mounted on said third part and laterally beyond the corresponding side of said base.

2. A cutter for sheet glass, said cutter comprising a base for resting on the sheet glass, a longitudinal block on said base having one side 75

- spaced inwardly from the corresponding side of the base, said side of the block being formed intermediate its upper and lower edges with a longitudinal groove, and the top of said block being 5 formed with a longitudinal groove, a slide having a first part slidable on said top of the block, the underside of said first part with a longitudinal groove registering the longitudinal groove in the top of the block, said slide including a second part 10 depending from the first part and slidably engaging said side of the block and formed with a longitudinal groove registering with the groove in said side of the block, a third part depending from said second part and slidably engaging the 15 top of the base, glass cutting means on and extending laterally outwardly from said second part beyond the corresponding side of the base, and rollers arranged in the registering grooves and rollable therealong, said rollers being of sufficient diameter to extend in both of the registering 20 grooves.
3. A cutter for sheet glass, said cutter comprising a base for resting on the sheet glass, a longitudinal block on said base having one side spaced inwardly from the corresponding side of the base, said side of the block being formed intermediate its upper and lower edges with a longitudinal groove, and the top of said block being 25 formed with a longitudinal groove, a slide having a first part slidable on said top of the block, the underside of said first part with a longitudinal groove registering the longitudinal groove in the top of the block, said slide including a second part depending from the first part and slidably engaging said side of the block and formed with a longitudinal groove registering with the groove in said side of the block, a third part depending from 30 said second part and slidably engaging the top of the base, glass cutting means on and extending laterally outwardly from said second part beyond the corresponding side of the base, and rollers arranged in the registering grooves and rollable therealong, said rollers being of sufficient diameter to extend in both of the registering 35 grooves, a motor fixed on the upper portion of said slide, and means operatively connecting said motor with the opposite side of said block.
6. A cutter for sheet glass, said cutter comprising a base for resting on the sheet glass, a longitudinal block on said base having one side spaced inwardly from the corresponding side of the base, said side of the block being formed intermediate its upper and lower edges with a longitudinal groove, and the top of said block being 40 formed with a longitudinal groove, a slide having a first part slidable on said top of the block, the underside of said first part with a longitudinal groove registering the longitudinal groove in the top of the block, said slide including a second part depending from the first part and slidably engaging said side of the block and formed with a longitudinal groove registering with the groove in said side of the block, a third part depending 45 from said second part and slidably engaging the top of the base, glass cutting means on and extending laterally outwardly from said second part beyond the corresponding side of the base, and rollers arranged in the registering grooves and rollable 50 therealong, said rollers being of sufficient diameter to extend in both of the registering grooves, 55 a motor fixed on the upper portion of said block, a rack connected to the side of said block opposite that having the longitudinal groove, and gearing connecting operatively to said rack.
4. A cutter for sheet glass, said cutter comprising a base for resting on the sheet glass, a longitudinal block on said base having one side spaced inwardly from the corresponding side of the base, 60 said side of the block being formed intermediate its upper and lower edges with a longitudinal groove, and the top of said block being formed with a longitudinal groove, a slide having a first part slidable on said top of the block, the underside of said first part with a longitudinal groove registering the longitudinal groove in the top of the block, said slide including a second part depending from the first part and slidably engaging 65 said side of the block and formed with a longitudinal groove registering with the groove in said side of the block, a third part depending from said second part and slidably engaging the top of the base, glass cutting means on and extending laterally outwardly from said second part beyond 70 the corresponding side of the base, and rollers 75
5. A cutter for sheet glass, said cutter comprising a base for resting on the sheet glass, a longitudinal block on said base having one side spaced inwardly from the corresponding side of the base, said side of the block being formed intermediate its upper and lower edges with a longitudinal groove, and the top of said block being formed with a longitudinal groove, a slide having a first part slidable on said top of the block, the underside of said first part with a longitudinal groove registering the longitudinal groove in the top of the block, said slide including a second part 10 depending from the first part and slidably engaging said side of the block and formed with a longitudinal groove registering with the groove in said side of the block, a third part depending from 15 said second part and slidably engaging the top of the base, glass cutting means on and extending laterally outwardly from said second part beyond the corresponding side of the base, and rollers arranged in the registering grooves and rollable 20 therealong, said rollers being of sufficient diameter to extend in both of the registering grooves, 25 a motor fixed on the upper portion of said slide, and means operatively connecting said motor with the opposite side of said block.
7. A cutter for sheet glass, said cutter comprising a base for resting on the sheet glass, a longitudinal block on said base having one side spaced inwardly from the corresponding side of the base, said side of the block being formed intermediate its upper and lower edges with a longitudinal groove, and the top of said block being formed with a longitudinal groove, a slide having a first part slidable on said top of the block, the underside of said first part with a longitudinal groove registering the longitudinal groove in the top of the block, said slide including a second 30 part depending from the first part and slidably engaging said side of the block and formed with a longitudinal groove registering with the groove in said side of the block, a third part depending from 35 said second part and slidably engaging the top of the base, glass cutting means on and extending laterally outwardly from said second part beyond the corresponding side of the base, and rollers arranged in the registering grooves and rollable 40 therealong, said rollers being of sufficient diameter to extend in both of the registering grooves, 45 a motor fixed on the upper portion of said block, a rack connected to the side of said block opposite that having the longitudinal groove, and gearing connecting operatively to said rack.

part depending from the first part and slidably engaging said side of the block and formed with a longitudinal groove registering with the groove in said side of the block, a third part depending 5 from said second part and slidably engaging the top of the base, glass cutting means on and extending laterally outwardly from said second part beyond the corresponding side of the base, and rollers arranged in the registering grooves and 10 rollable therealong, said rollers being of sufficient diameter to extend in both of the registering grooves, an electric motor fixed on the upper portion of said block, a rack connected to the side of said block opposite that having the longitudinal 15 groove, and gearing connecting operatively to said rack, contact rails carried on said rack, and contact brush means engaged with said contact rails and carried by a member extending laterally from said slide.

20 8. A cutter for sheet glass, said cutter comprising a base for resting on the sheet glass, a longitudinal block on said base having one side spaced inwardly from the corresponding side of the base, said side of the block being formed intermediate 25 its upper and lower edges with a longitudinal groove, and the top of said block being formed with a longitudinal groove, a slide having a first part 30 slidable on said top of the block, the underside of said first part with a longitudinal groove register- 35 tering the longitudinal groove in the top of the block, said slide including a second part depend- 40 ing from the first part and slidably engaging said side of the block and formed with a longitudinal groove registering with the groove in said 45 side of the block, a third part depending from said second part and slidably engaging the top of the base, glass cutting means on and extending laterally outwardly from said second part beyond the corresponding side of the base, and rollers ar- 50 ranged in the registering grooves and rollable therealong, said rollers being of sufficient diameter to extend in both of the registering grooves, said glass cutting means comprising a pair of rods extending laterally outwardly from longitudinally spaced points on the outer side of said second part, a body having end members slidably mounted on said bars so as to be laterally adjustable in a substantially horizontal plane, said body having a member on its outer end slidably adjustable in a vertical plane, said member including a cutter

element engageable with the sheet glass for cutting the same.

9. A cutter for sheet glass, said cutter comprising a base for resting on the sheet glass, a longitudinal block on said base having one side spaced inwardly from the corresponding side of the base, said side of the block being formed intermediate its upper and lower edges with a longitudinal groove, and the top of said block being formed with a longitudinal groove, a slide having a first part 5 slidable on said top of the block, the underside of said first part with a longitudinal groove register- 10 ing the longitudinal groove in the top of the block, said slide including a second part depend- 15 ing from the first part and slidably engaging said side of the block and formed with a longitudinal groove register- 20 ing with the groove in said side of the block, a third part depending from said second part and slidably engaging the top of the base, glass cutting means on and extending laterally outwardly from said second part beyond the corresponding side of the base, and rollers ar- 25 ranged in the registering grooves and rollable therealong, said rollers being of sufficient diameter to extend in both of the registering grooves, 30 said glass cutting means comprising a pair of rods extending laterally outwardly from longitudinally spaced points on the outer side of said second part, a body having end members slidably mounted on said bars so as to be laterally adjustable in a substantially horizontal plane, said body having a member on its outer end slidably adjustable in a vertical plane, said member including a cutter 35 element engageable with the sheet glass for cutting the same.

10. Glass cutting means for attachment to the slide of a sheet glass cutting machine, said glass cutting means comprising a pair of rods extending laterally from the side of said slide, a body 40 having end members slidably mounted on said rods so that said body may be laterally adjusted toward and away from the side of said slide, said body having a member on its laterally outward end 45 slidably adjustable relative to the body in a vertical plane, said member including a cutter element engageable with the sheet glass for cutting the same, said element including a cutting point and vertically acting means connecting the same to said member.

THOMAS McDOWELL.
